(57) CLAIM

The ornamental design for a jewelry article for use as a pendant or chain, as shown and described.

DESCRIPTION

FIG. 1 is a front view of a pendant showing my new design; FIG. 2 is a front perspective view thereof;

FIG. 3 is a right side view thereof;

FIG. 4 is a rear view thereof;

FIG. 5 is a rear perspective view thereof;

FIG. 6 is a left side view thereof;

FIG. 7 is a front view of a chain showing my new design;

FIG. 8 is a front perspective view thereof;

FIG. 9 is a right side view thereof;

FIG. 10 is a rear view thereof;

FIG. 11 is a rear perspective view thereof; and,

FIG. 12 is a left side view thereof.

The broken lines shown in the drawings illustrate portions of the jewelry article for use as a pendant or chain that form no part of the claimed design.
